RADIO VOLUME CONTROL

James L. Getaz, Maryville, Tenn.

Application May 9, 1936, Serial No. 78,808
Renewed August 28, 1939

20 Claims. (Cl. 250—6)

This invention relates to the electrical transmission of intelligence signals, such as sound signals and particularly to the control of the volume of the sound received.

- 5 The purposes of this invention are as follows:
1. To control this volume of sound as received so that it will be independent of the strength of the received signal.
  2. To control this volume of sound as received 10 so that it will be independent of contractions in volume which may be made at the transmitting station by the transmitting operator.
  3. To control the volume of sound as received so that the receiving set will have small amplification when no signal is being received.

4. To automatically maintain the same volume of sound received in changing from one transmitting station to another station of different strength.
- 20 5. To provide means for controlling the volume of sound at the receiving set so that the volume of sound as received will be proportional to the volume of sound as originally produced.

In Fig. 1 is shown diagrammatically the connections to provide for such control at the broadcasting station.

In Fig. 2 is shown the connections for the receiving set.

The basic principle involved in obtaining such volume control is to utilize an arrow band of frequency, and at the transmitting station to generate waves within this band so that the frequency of the waves will vary with the volume of the sound produced. These waves constitute signals denoting the volume of the original sound and are used in radio transmission to modulate the carrier wave, and may be referred to as volume signals. The carrier is thus modulated in two ways, it contains the regular modulation which corresponds in frequency and amplitude with the original sound, and in addition it carries another modulation consisting of these volume signals. In the transmitting wave, the amplitude of these volume signals is not of particular importance, except that they should produce a fair amount of modulation. Their usefulness depends on the variations of their frequency, and we thus have along with the usual signals, a special band of signals representing volume by frequency 50 rather than by amplitude.

The principles of this invention may be applied to any means for the transmission or reproduction of sound in which electrical signals are used to represent the sound waves. These principles 55 may be used for controlling the amplification of

electrical signals representing sound waves which are reproduced from phonograph records or motion picture films.

To avoid distortion of the regular signals, these volume signals may be confined to a band below 5 audible frequency, from a fraction of one cycle per second to about twenty-five cycles.

In Fig. 1 the microphone 1 is supplied with current by the battery 2 and is connected by the transformer 3 to the amplifying circuit consisting of the battery 39, the triode 40 and the battery 45, this circuit includes the transformer 38 which connects to the transmitter modulator through the line 43.

This transformer 3 is also connected to the 15 amplifying circuit consisting of the battery 4, the battery 6, the triode 5, and the transformer 7. The current from the transformer 7 is rectified by the diode 10, thus producing a direct current envelope which corresponds with the variation in 20 volume of the current generated in the microphone circuit. In the circuit of this diode 10 is a resistance 8 shunted by a condenser 9, and the ends of this resistance are connected to the grid 25 and filament of the triode 12. By varying resistance 8 and the capacity of the condenser 9 it is possible to control the frequency with which the rectifier will follow the volume change. The circuit of this triode 12 amplifies the voltage 30 variations in the envelope produced by the diode 10, and this circuit contains the battery 11, the battery 14, the choke coil 13, and the saturation reactor 15. This saturation reactor is connected in the circuit of the oscillating tube 19, which consists of the feed back coils 16 and 17, the condenser 18, the battery 22 and the resistance 21 which is by-passed by the condenser 20. This 35 oscillating circuit is adjusted to produce oscillations of medium frequency, the frequency of these oscillations are varied by the saturation reactor 15, and are transmitted to the grid of the triode 33 by connections to the transformer 23.

Another oscillating circuit consists of the triode 30, the feed back coils 25 and 26, the condenser 27, the battery 31 and the resistance 29, which 45 is by-passed by the condenser 28. The circuit is adjusted to produce oscillations of about the same frequency as those produced by the tube 19 and is connected to the grid of the triode 33 by the transformer 24. This circuit maintains a constant frequency.

The frequency of the beats between these two oscillating circuits varies as the frequency of the oscillations, produced by tube 19, is varied by the saturation reactor 15. By proper adjustment of 50 55

the two oscillating circuits the frequency of these beats may be made to vary inversely with the amplitude of the direct current envelope and they may be confined to a narrow band below the 5 audible frequency. The oscillations of these two circuits are rectified by triode 33 in the circuit consisting of the battery 32, the battery 46 and the condenser 34, and the beats are transmitted through the transformer 35 and the low pass filter 36, which filters out any harmonics. These 10 low frequency beats are connected through the transformer 37 to the line 44 leading to the transmitter modulator. The connection 44 is set on the resistance 42 to fix the amplitude of the 15 volume signals, and the line 43 may be varied in its connection to the resistance 41, so as to vary the modulation of the main signals. This variation does not affect the modulation which is made by the volume signals.

20 In Fig. 2 the signals are received from the antenna 50 through the transformer 51 and are amplified in two or more circuits consisting of the pentode 54, the battery 55, the condenser 52 and the tuning condenser 53, and transformer 56, 25 also the pentode 59, battery 60, condenser 57, tuning condenser 58, and transformer 61. These signals are rectified by the diode 65, in the circuit containing the tuning condenser 62, the resistance 64, which is by-passed by the condenser 30 63. The audio frequency is amplified in the circuit containing the triode 67, the battery 68, the battery 66, and the transformer 69. From the transformer 69, the main signals pass through the high pass filter 70 which admits all frequencies 35 in the audible range. The frequencies below the audible range which constitute the volume signals, mentioned above, pass through the low pass filter 75 which does not admit the frequencies in the audible range.

40 The main signals after passing through the filter 70 are further amplified in the circuit containing the triode 72, the battery 73, battery 71 and transformer 74 and from thence to the loud speaker through the lines 96 and 97.

45 The volume signals after passing through the low pass filter 75 are amplified in the circuit consisting of the pentode 77, battery 78, battery 76 and transformer 79. This pentode 77 is charged with a low plate voltage low screen voltage and a high grid signal voltage so that the 50 amplification is always in excess of the capacity of the tube. Additional amplification circuits may be included between the pentode 77 and the low pass filter 75, or regenerative amplification 55 may be used to amplify the volume signals to tube capacity. This enables the tube to maintain an output of constant amplitude irrespective of the amplitude of the volume signal, provided volume signals are being transmitted by the broadcasting station.

60 From the transformer 79, these volume signals pass through a corrector circuit consisting of the triode 80, battery 81, battery 82, resistance 83, condenser 84, inductance 85, and resistance 86. The condenser 84 is of sufficient capacity to transmit the volume signals of lowest frequency. This circuit varies the drop in voltage across the 65 resistance 86 inversely to the frequency of the volume signals. The higher frequencies are 70 choked by the impedance of the coil 85 and are divided between this coil and the resistance 83, the lower the frequency a larger proportion of the current passes through the coil 85 and the resistance 86. Connected across the resistance 86 75 is a rectifying circuit consisting of the diode 87,

resistance 89, which is by-passed by the condenser 88. The rectification of these low frequency signals produces an envelope in which the amplitude varies with the frequency of the volume signals.

In a similar manner the audio signals from the transformer 74 are rectified in the circuit containing the diode 91, and resistance 93, which is by-passed by the condenser 92. This produces an envelope the amplitude of which varies with the 10 voltage of the audio signals, these signals being transmitted to the loud speaker by the lines 96 and 97.

The envelope produced by the diode 91 varies in amplitude with the amplitude of the signals 15 as actually received.

The envelope produced by the diode 87 varies inversely as the frequency of the volume signals sent out by the broadcasting station. If the circuits are properly adjusted the two envelopes 20 should be practically the same in amplitude at all times. The positive ends of the resistances 89 and 93 are connected to each other. The negative end of resistance 89 is connected by the wire 94 to the filaments of pentodes 54 and 59. The 25 negative end of resistance 93 is connected by the wire 95 to the grids of the pentodes 54 and 59. By these connections the drop in voltage across the resistor 89 is compared with the drop in voltage across the resistor 93. The drop in voltage 30 across the resistor 89 varies with the varying voltage of the envelope in that circuit and is representative of the strength of signals as transmitted. The drop in voltage across the resistor 93 varies with the varying voltage of the envelope 35 in that circuit and is representative of the strength of the signals as received. If the envelope of the signals as actually received has greater amplitude than the envelope of the volume signals, the grids of the pentodes 54 and 59 40 will be made more negative by the connection to the negative side of resistance 93 and the volume of the received signals will be reduced until the amplitude of the two envelopes are equal.

If the envelope of the volume signals as produced by the diode 87 is greater than the envelope of the signals actually received, the filaments of the pentodes 54 and 59 will be made 45 more negative with reference to the grids, which increases the grid voltage and increases the volume of the received signals until the envelopes 50 are equal.

The operation of these circuits may be summarized as follows: In the transmitting set the signals are amplified and then rectified in the 55 diode 10 so as to produce an envelope, not of the signal itself but of its amplitude.

This direct current which varies with volume of sound to be transmitted is used to vary the frequency of the oscillating tube 19. The oscillations of this circuit are combined with the oscillations on the circuit of triode 30, in which the oscillations are constant. The beats of these two oscillating circuits are rectified in the circuit of the triode 33, passed through the low pass filter 60 36 and connected to the transmitter modulator. The beats of these circuits are of such low frequency as to not be audible, or interfere with the 65 modulation of the carrier for transmission of the regular signals.

In the receiving set after the signals have been 70 amplified and detected in the usual manner, the audio frequencies are divided, the audible frequencies passing through the filter 70 and after further amplification to the loud speaker. The 75

audio frequencies below the audible range are the volume signals, these are amplified in a tube 17 which is overloaded so that the amplitude of these signals is not proportional to the strength 5 of the signals received but is fixed by the capacity of the tube.

These volume signals are then passed through the corrector circuit of the triode 80 by which their amplitude is made inversely proportional to 10 their frequency, and they are then rectified in the circuit of the diode 81 as mentioned above. The voltage of this circuit forms the standard by which the volume is to be controlled. By connecting lines 94 and 95 to the grids and filaments of several stages of amplification, a close 15 regulation of volume may be automatically obtained in tuning from one station to another, if these stations are provided with volume signals. As mentioned on page 1, a purpose of this invention is to make the volume of the sound received proportional to the sound transmitted. It includes means for correcting distortion in 20 volume from all causes in electrical transmission and reception, such distortion as is caused by the curvature of the grid voltage, plate current curve 25 of the tubes used in audio frequency amplification. It also includes means for limiting the noise received, so that the volume of the noise plus the volume of the signal received would be 30 equal to what the volume of the signal should be if noise were not being received.

This invention is shown and described as referring to the transmission and reproduction of electrical signals which represent sound signals. 35 It is apparent that it may be applied to electrical signals which represent other forms of intelligence signals besides sound, and it is intended to include the control of electrical signals which are used to transmit intelligence in any form.

40 I claim:

1. In an electrical receiving set, means for receiving a carrier wave, means for receiving intelligence signals by demodulating said carrier wave, means for receiving signals which indicate the volume of the sound being transmitted and means for comparing an intensity derived from 45 said intelligence signals as received with the volume of sound transmitted as indicated by said volume signals, means for using said comparison for correcting the rate of amplification of said intelligence signals.

2. In an electrical receiving set, means for receiving signals which vary in frequency with the volume of sound transmitted, means for producing an envelope derived from said volume signals which varies in amplitude in proportion to their frequency, means for receiving sound signals, means for producing an envelope derived from said sound signals which varies in amplitude in proportion to the amplitude of said sound signals, means for utilizing the voltage of these two envelope currents to regulate the volume of sound produced.

3. The method of receiving signal energy from 45 a carrier medium modulated with electrical signals and an additional modulating current, which comprises, deriving the electrical signals from said carrier medium, deriving said additional modulating current from said carrier medium, comparing the strength of said signals with the strength of the signals transmitted as represented by said additional modulating current, and controlling the degree of amplification of said signals by a voltage which corresponds to 50 the difference between the strength of said sig-

nals as received and the strength of said signals, when transmitted, as represented by said additional modulating current.

4. The steps in a method of deriving signal energy from a carrier medium modulated with electrical signals and an additional modulating current which comprise, deriving from said carrier medium said electrical signals, deriving from the carrier medium said additional modulating current, amplifying said modulating current to 10 a fixed amplitude, amplifying said modulating current to produce a difference of potential which varies in accordance with the variations of frequency of said modulating current, rectifying said differences of potential, rectifying said electrical signals, using the comparative strength of said rectified difference of potential and said rectified signals to control the degrees of amplification of said signals.

5. In an electrical receiving set, means for receiving sound signals, means for receiving control signals which represent by their frequency the volume of the sound being transmitted, means for rectifying said control signals, means for obtaining potentials from said control signals 25 which vary with their frequency, means for amplifying said sound signals, means for regulating said amplification by said potentials, means for rectifying said sound signals and obtaining potentials representing their amplitude, means for 30 comparing the potentials representing the volume of said amplified signals with the potential representing the volume of sound transmitted as represented by said control signals.

6. In an electrical receiving set, means for receiving a carrier wave modulated with sound signals, means for deriving sound signals from said carrier wave, means for amplifying said sound signals, means for obtaining a voltage proportional to the volume of said amplified 40 sound signals, means for deriving control signals of variable frequency from said carrier wave, means for obtaining a voltage which varies with the frequency of said control signals, means for controlling said amplification by the difference 45 between said voltages.

7. In an electrical receiving set, means for receiving a carrier wave of constant frequency containing sound signals and also signals representing the volume of sound transmitted, means for deriving sound signals from said carrier wave, means for deriving potentials from said carrier wave which represent the volume of sound being transmitted, means for comparing the potentials representing the volume of sound as received 50 with the potentials representing the volume of sound transmitted as indicated by said volume signals, means for using said comparison for controlling the amplification of said carrier.

8. In an electrical receiving set, means for receiving a carrier wave modulated with sound signals, means for deriving sound signals from said carrier wave which vary in frequency over the whole audio-frequency band, means for amplifying said sound signals in said receiving set 65 at all of said frequencies, means for deriving volume signals from said carrier wave which represent the volume of sound being transmitted, means for comparing the potentials representing the volume of said sound signals as amplified 70 at all audio frequencies, with the potentials representing the volume of sound being transmitted as indicated by said volume signals, means for using said comparison to control the rate of amplification of said sound signals.

9. In an electrical receiving set, means for receiving signals which represent the volume of the sound being transmitted, means for amplifying said signals to a constant amplitude, and 5 means for comparing the potentials representing the volume of sound as received with the potentials representing the volume of sound transmitted as indicated by said signals, means for using said comparison to control the volume of 10 sound received.
10. In an electrical receiving set, means for receiving a carrier wave containing control signals and intelligence signals, means for rectifying said carrier wave, means for deriving intelligence signals from the modulation of said carrier wave, means for amplifying said intelligence signals, means for obtaining a voltage representative of the amplitude of said intelligence signals, means for comparing said representative 15 voltage with a voltage derived from said control signals, and means for utilizing the difference between said voltages to increase and decrease amplification of said signals.
11. In an electrical receiving set, means for receiving a carrier wave which is modulated with a frequency control and with sound signals, means for rectifying said carrier wave, means for deriving signals from the modulation of said carrier wave, means for amplifying said signals, 20 means for obtaining a voltage representative of the amplitude of said signals, means for comparing said representative voltage with a voltage to which it is desired for the signals to be amplified, and means for regulating the amplification 25 of said signals, so that their voltage will correspond with said desired voltage.
12. In an electrical receiving set, means for receiving a carrier wave which is modulated with a frequency control and with sound signals, 30 means for rectifying said carrier wave, means for deriving sound signals from the modulation of said carrier wave, means for amplifying said signals, means for obtaining a voltage representative of the amplitude of said signals, means 35 for comparing said representative voltage with a voltage derived from said frequency control to which it is desired for said signals to be amplified, and automatic means for increasing the amplification of said signals when said representative voltage is less than said desired voltage.
13. In an electrical receiving set, means for receiving a carrier wave of substantially constant frequency which contains intelligence signals and volume control signals, means for deriving said control signals from said carrier, 40 means for deriving said intelligence signals from said carrier, means for utilizing said control signals in combination with said intelligence signals to control the rate of amplification of said carrier.
14. In an electrical receiving set, means for receiving intelligence signals and control signals which indicate by their frequency the volume of the intelligence signals transmitted, 45 means for obtaining potentials representing the amplitude of said intelligence signals, means for obtaining potentials representing the frequency of said control signals, means for controlling the rate of amplification of said intelligence signals by the combined action of said potentials.
15. In an electrical receiving set, means for receiving a carrier wave of substantially constant frequency which contains intelligence signals and control signals which indicate by their frequency the volume of the intelligence signals transmitted, 50 means for obtaining potentials representing the amplitude of said intelligence signals, means for obtaining potentials representing the frequency of said control signals, means for controlling the rate of amplification of said carrier by the combined action of said potentials.
16. In an electrical receiving set, means for receiving a carrier wave of substantially constant frequency which contains intelligence signals and control signals which indicate by their frequency the volume of the intelligence signals transmitted, 55 means for obtaining potentials representing the amplitude of said intelligence signals, means for obtaining potentials representing the frequency of said control signals, means for controlling the rate of amplification of said carrier by the difference between said potentials.
17. The steps in receiving a carrier wave of substantially constant frequency, modulated with 60 intelligence signals, and modulated with control signals of variable frequency, which comprise, deriving said intelligence signals from said carrier, obtaining potentials representing the amplitude of said intelligence signals, deriving said control signals from said carrier, obtaining potentials representing the frequency of said control signals, regulating the rate of amplification of said carrier by the combined action of said potentials.
18. The steps in receiving a carrier wave of substantially constant frequency, modulated with intelligence signals and control signals of variable frequency, which comprise, deriving said intelligence signals from said carrier, obtaining 65 potentials representing the amplitude of said intelligence signals, deriving said control signals from said carrier, obtaining potentials representing the frequency of said control signals, regulating the rate of amplification of said intelligence signals by the combined action of said potentials.
19. The steps in receiving a carrier wave of substantially constant frequency modulated with intelligence signals, and modulated with control signals of variable frequency, which comprise, deriving said control signals from said carrier, amplifying said control signals to a constant amplitude, obtaining potentials which represent the frequency of said control signals, obtaining potentials representing the amplitude of said intelligence signals, regulating the rate of amplification of said intelligence signals by the difference between said potentials.
20. A method of receiving and amplifying electrical signals which comprises, receiving intelligence signals, receiving control signals which indicate by their frequency the volume of the intelligence signals transmitted, obtaining potentials representing the amplitude of said intelligence signals, obtaining potentials representing the frequency of said control signals, controlling the rate of amplification of said intelligence signals by the combined action of said potentials.
